UNITED STATES PATENT OFFICE.

WESLEY C. GAY, OF WRENS, GEORGIA.

FOLDING WIRE FENCE.

SPECIFICATION forming part of Letters Patent No. 794,933, dated July 18, 1905.
Application filed November 23, 1904. Serial No. 233,968.

To all whom it may concern:

Be it known that I, WESLEY C. GAY, a citizen of the United States, residing at Wrens, in the county of Jefferson and State of Georgia, have invented certain new and useful Improvements in Folding Wire Fences, of which the following is a specification.

My invention relates to folding wire fences, and directly belongs to the class of those which are built up of separable sections or panels all substantially alike in structural detail and which may be taken down and set up by hand practically without employing tools or other appliances.

The object of my invention is to produce a wire fence possessing the general characteristics mentioned, but having a particular and peculiar construction and arrangement of parts constituting the panels or divisions, which fold one upon another when desired, as hereinafter specified.

I accomplish the stated object by fashioning and associating parts as illustrated in the accompanying drawings, of which—

Figure 1 represents a front view showing the special construction and arrangement of the panels and posts; and Fig. 2 is a view of one of the posts alone, showing the manner of supporting and bracing it in an erect position. Fig. 3 represents an enlarged side view of one of the posts and its braces and shows the loose connection between post and braces, and it also shows that the post and braces pass through the foot-plate, which is drawn partly in section. Fig. 4 is a plan view of the foot-plate, drawn according to the scale of Fig. 3.

Like letters designate like parts throughout.

Considering the drawings, letter A marks the posts, B the main cross-wires of the panels, C the intermediate cross-wires of the panels, and D the diagonal wires.

Any chosen means, such as tying or soldering, may be employed to secure the wires together wherever they cross.

In Fig. 2 will be noted the inclined braces E, having eyes e, through which the post passes. Collars F are clamped around the

post above and below eyes e, as shown. The 50 lower ends of the post and braces pass through the footing-plate G and extend into the ground, as illustrated. It will be here noted that the footing G may be slipped from the ends of braces and post when those parts are pulled 55 out of the ground, and when the footing is thus removed the braces may be arranged to lie flat against the post. It will be understood from Figs. 2 and 3 that eyes e are large enough and sufficiently loose upon the posts 60 to permit the braces E to swing inwardly toward the posts. The footing-plate also is placed for transportation flatwise upon the fence-panel. The braces are shown in broken lines against the post. By extending the 65 braces and passing them and the post through the footing and then forcing the ends of the braces and post sufficiently into the earth, the footing resting upon the surface, the posts are held firmly in an upright position. 70

Each panel of fence consists, ordinarily, of two lattices, upper and lower, each of which has the vertical side wires H looped together, whereby the lower lattice is suspended from the upper one.

All the main cross-wires B of all the panels are provided with eyes b, through which the posts are passed, and below and above the upper eyes b the retaining-collars J are secured to the posts. 75

It will be seen from Fig. 1 that, compared with the upper, the lower lattice has twice the number of diagonal wires and additional main and intermediate cross-wires. This lattice being near the ground is given lesser openings 85 to prevent the entrance of fowls or cats or dogs. The construction generally considered does not differ from that of the upper lattice.

In the middle of Fig. 1 will be observed the long diagonals K, extending from top to bottom of two adjacent panels and having the eyes k, through which the posts pass. These diagonals are used by me at the corners of the fence as an additional means for stiffening the fence at the corners. They are not absolutely 95 essential and may be omitted, if desired.

I am aware that wire fences have been constructed in which the panels may be folded

one upon the other, and I do not claim that feature broadly.

What I claim is—

1. In a folding wire fence, the combination with vertical posts adapted to be inserted into the ground, of wire-fence panels pivotally supported by the posts, foot-plates arranged upon the surface of the ground and having holes at middle points and near their ends, and braces loosely secured to the posts and adapted to be passed in an inclined direction through the end holes of the foot-plates and inserted into the ground, the said posts being passed through the said middle holes of the foot-plates, substantially as described.
2. In a folding wire fence, the combination

with the posts, of panels comprising upper and lower lattices having main cross-wires provided with eyes encircling the posts, the said panels comprising also the vertical side wires, the intermediate cross-wires, and the diagonal wires, and devices acting upon the uppermost eyes of the said main cross-wires for supporting the said panels upon the posts, the said lower lattice being supported by the said upper lattice, substantially as described.

In testimony whereof I affix my signature in presence of two witnesses.

WESLEY C. GAY.

ABRAM RUSSELL,
JOSEPH A. DENTON.
